TOY GRANDFATHER CLOCK OR SIMILAR ARTICLE

Irwin Cohn, Leominster, Mass., assignor to Great Ameri-
can Plastics Company, Fitchburg, Mass., a corporation
of Massachusetts

Filed Feb. 15, 1960, Ser. No. 59,390

Term of patent 3½ years

(Cl. D34—15)

FIG.3

FIG.4

FIG.5

FIG.6

FIG.7

Fig. 1 is a front elevational view of a toy grandfather clock embodying the invention;

Fig. 2 is a side elevational view thereof;

Fig. 3 is a view showing the outer outline thereof, taken on plane 3-3 of Fig. 1;

Fig. 4 is a view showing the outer outline thereof, taken on plane 4-4 of Fig. 1;

Fig. 5 is a view showing the outer outline thereof, taken on plane 5-5 of Fig. 1;

Fig. 6 is a view showing the outer outline thereof, taken on plane 6-6 of Fig. 1; and

Fig. 7 is a view showing the outer outline thereof, taken on plane 7-7 of Fig. 1.

I claim:

The ornamental design for a toy grandfather clock or similar article, substantially as shown.
